THERMOSTATIC VENT VALVE FOR
RADIATORS

Edward Jacobus, East Orange, N. J.

Application August 15, 1944, Serial No. 549,557

1 Claim. (Cl. 236—62)

This invention relates in general to thermostatic valves of the general type shown in my United States Patent No. 1,547,652 dated July 28, 1925, to control the flow of a fluid or fluids therethrough in accordance with the temperature of the fluids, and more particularly the invention relates to a valve having thermostatically controlled means for holding the valve open to permit fluids of a certain range of temperatures to pass therethrough and closing the valve to prevent fluids of temperatures above said range from escaping through the valve.

Valves of this type include a substantially semi-circular expansible bimetallic thermostatic strip secured at one end to the casing of the valve with the other end disposed substantially opposite and distantly spaced from the valve seat, and an elongate valve rod having at one end a valve head slidably guided in and to cooperate with said valve seat and provided at its other end with a reduced portion loosely fitted within an opening in the second-mentioned end of said thermostatic strip, there being a shoulder at the inner end of said reduced portion abutting said thermostatic strip, whereby upon expansion and contraction of said thermostatic strip said valve rod will be moved longitudinally to cause said valve head to engage and disengage said valve seat.

A prime object of the present invention is to provide in a valve of the general character described, novel and improved means for mounting and guiding the valve rod to permit complete freedom of movement of the thermostatic strip relatively to the valve rod in all directions laterally of the valve rod so as to ensure a high degree of sensitivity and accuracy in seating and unseating of the valve head.

Another object is to provide in such a valve means which shall include a thin sheet metal casting and novel and improved means for connecting thereto a threaded nipple for attaching the valve to a radiator; and to obtain other advantages and results that will be brought out by the following description in conjunction with the accompanying drawing in which

Figure 1 is a side elevational view of a valve constructed in accordance with my invention, showing the same applied to a radiator;

Figure 2 is an enlarged transverse vertical sectional view through the valve taken on line 2—2 of Figure 3.

Figure 3 is an enlarged front elevational view of the valve showing the latter removed from the radiator.

Figure 4 is an end elevational view of the valve

5 with one end wall removed, showing the mounting of the thermostatic strip and the valve rod, and

Figure 5 is a detached plan view of the nipple for attaching the valve to a radiator.

In the specific embodiment of the invention shown on the drawing, the reference character 1 designates a substantially hollow cylindrical casing closed at both ends, said casing being conveniently formed of sheet metal by a drawing operation and having one end in the form of a cover 2 to which is secured a threaded nipple 3 for connecting the valve to a radiator A of a steam heating system. The casing 1 is provided at one side thereof with an outlet passage 4 which may be formed in a nipple 5 secured to the casing by means of a nut 6 threaded on the inner end thereof. The inner end of said nipple 5 is formed with a valve seat 7 with which cooperates a valve head 8 carried by a valve rod 9 mounted on a curved thermostatic strip 10 preferably bimetallic, one end of which is secured to the casing adjacent the valve seat 7.

In the present instance one end of the thermostatic strip 10 is provided with an opening 11 to slip over the inner end of the nipple 5 between the nut 6 and a spacing washer 12 which abuts the casing, whereby the strip is securely fastened to the interior of the casing. The opposite end of the thermostatic strip is disposed substantially opposite the valve seat 7 and distantly spaced therefrom, said end being longitudinally slit at 13 inwardly from its extremity and having a portion at one side of the slit bent outwardly 35 toward the casing as indicated at 14.

The valve rod 9 is of a length to extend between the free end of the thermostatic strip and the valve seat 7, and the end of said rod opposite the valve head 8, is preferably rounded and frictionally and loosely abuts the side of the thermostatic strip. To hold said end of the valve rod against lateral movement, a guide bracket 15 is secured to one wall of the casing and has an opening 16 in which the valve rod 9 is freely slideable longitudinally.

In operation of the valve, when the radiator A is filled with air and steam is admitted thereto, the semi-circular thermostatic strip 10 is distended so as to maintain the valve head 8 out of engagement with the seat 7 and permit escape of air from the casing. When steam enters the valve casing, the thermostatic strip is flexed so as to cause the free end thereof to move toward and transversely of the valve seat 7. This action exerts a longitudinal thrust on the valve rod 9

which causes the valve head 8 to engage the seat 7 and prevent the escape of steam through the outlet 4.

With this construction, it will be observed that the thermostatic strip may move freely in all directions relatively to the valve rod and laterally of the latter, and the valve rod is held against lateral movement and guided in its longitudinal movement by the guide bracket 14. Accordingly all possibility of the valve rod being tilted or becoming jammed, is eliminated and a high degree of sensitivity and accuracy in seating of the valve head is insured.

The end of the valve rod carrying the valve head is guided by the valve head sliding in the concave valve seat, and to prevent complete disengagement of the valve rod from the valve seat, the outwardly bent portion 14 at the free extremity of the thermostatic strip will engage the valve casing 1 to limit such movement of the thermostatic strip as would permit the valve head to become completely detached from the valve seat.

For simplicity in manufacture, the nipple 3 is formed separately from the casing 1 which is made of sheet metal, and the nipple is inserted through an opening 17 in said casing. The nipple is formed with an integral flange 18 to abut the inner surface of the wall of the casing and is provided with a notch 19 in which is seated a rivet 20 the opposite ends of which are upset over the outer surface of the wall of the casing and over the inner end of the nipple, as shown in Figure 2. This rivet and notch will prevent rotation of the nipple during the threading of valve into a radiator, and to provide a liquid-tight connection between the nipple and the casing, solder is flowed into the opening 17 around the nipple.

Preferably the valve head 8 is hemispherical so that it will accurately slide into contact with and snugly engage the valve seat.

When it is desired to adapt the valve to prevent the escape of water therethrough, a bell or float 21 may be rigidly secured to the valve rod 9, said float being so positioned with respect to the inlet 3 of the casing 1 that water entering

the casing will raise the float and move the valve rod 9 so as to cause closing engagement of the valve head and valve seat 7. It will be noted that the engagement of the valve rod 9 with thermostatic strip is particularly adapted for permitting the relative movement of the valve rod and the thermostatic strip as is necessary where a float is used.

It will be understood by those skilled in the art that the details of construction of the valve may be modified or changed within the spirit and scope of the invention.

What I claim is:

A valve of the character described comprising a casing having an inlet and an outlet surrounded by a concave valve seat, a substantially semi-circular thermostatic strip having one end fixedly secured to said casing adjacent said outlet and the other end distantly spaced from and substantially opposite said outlet and movable toward and from said outlet upon influx of hot and cold fluid respectively into said casing, a valve rod one end of which has an abutting slid-
15 able contact with the inner side of the second-mentioned end of said thermostatic strip, said valve rod having a hemi-spherical head at its other end to cooperate with said valve seat, whereby said valve rod is longitudinally moved by said thermostatic strip to cause engagement and disengagement of said valve head with and from said valve seat respectively and said seat limits lateral swinging of said valve head, a guide on said casing adjacent to but spaced from said inner side of the second-mentioned end of said thermostatic strip and having an opening in which said valve rod is freely longitudinally slidable, and a float fixedly connected to said valve rod between said second-mentioned end of said strip and said outlet to actuate said valve independently of said strip to close said outlet upon influx of liquid into said casing, said second-mentioned end of said thermostatic strip having means to abut said casing and limit movement of said end of said thermostatic strip away from said valve seat and thereby prevent displacement of said valve head away from said seat.

EDWARD JACOBUS.
